DESIGN FOR A HANDBAG

Henry Green, Far Rockaway, N. Y.

Application February 20, 1941, Serial No. 99,127

Term of patent 3½ years

To all whom it may concern:

Be it known that I, Henry Green, a subject of Poland and a resident of the United States of America, in the city of Far Rockaway, county of Queens, and State of New York, have invented a new, original, and ornamental Design for a Handbag, of which the following is a specification, reference being had to the accompanying drawing, forming part thereof, wherein the figure of the drawing is a front perspective view of a handbag showing my new design.

The rear and other end of the article have substantially the same appearance as the front and end shown.

I claim:

The ornamental design for a handbag, substantially as shown and described.

HENRY GREEN.
